COW-SHAPED SEAT FOR PLAYGROUND APPARATUS

Robert S. Wormser, Hillsdale, Mich., assignor to Game Time, Inc., Litchfield, Mich., a corporation of Michigan

Filed Apr. 1, 1968, Ser. No. 11,244

Term of patent 14 years

U.S. Cl. D34—15

Int. Cl. D21—04

FIG. 1 is an elevational view of the right side of a cow-shaped seat for playground apparatus in accord with my new design, the left side being identical in appearance,

FIG. 2 is a front elevational view,

FIG. 3 is a top plan view; and

FIG. 4 is a rear elevational view.

I claim:

The ornamental design for a cow-shaped seat for playground apparatus, substantially as shown and described.
